UNITED STATES PATENT OFFICE.

HERMAN WETTSTEIN, OF NEW YORK, N. Y.

BURGLAR-ALARM.

No. 909,492.

Specification of Letters Patent.

Patented Jan. 12, 1909.

Application filed May 18, 1908. Serial No. 433,410.

To all whom it may concern:

Be it known that I, HERMAN WETTSTEIN, a citizen of the United States, residing at New York city, Bronx, county and State of New York, have invented new and useful Improvements in Burglar-Alarms, of which the following is a specification.

This invention relates to a burglar alarm of novel construction which may be readily attached to a door and which is set off by the door as the latter is being swung open. In this way timely warning of an attempted unauthorized entry is given before the latter is effected.

15 In the accompanying drawing: Figure 1 is a front view of my improved burglar alarm; Fig. 2 a similar view with the bell removed and showing the parts in a different position; Fig. 3 an end view of Fig. 2, and Fig. 4 a cross section on line 4—4, Fig. 2.

A base plate 10, adapted to be screwed to a door frame 11, is provided with an arbor 12. On this arbor is fulcrumed a lever 13 bent twice at right angles, so as to be composed 25 of a pair of wings projecting in parallel planes in opposite directions from a common stem, (Fig. 3). The inner of these wings is perforated for the reception of arbor 12 by which it is pivoted to base plate 10 and is 30 provided with a lug 14 engaged by a spring 15 coiled around the arbor. An abutment 16 on plate 10 is adapted to retain lever 13 in such a position that its outer wing extends 35 at right angles to the door 17. The outer wing which is located in a plane in front of the door is provided with a finger 18 which is connected to such wing by a spring-influenced stop-hinge 19 that permits the finger to be swung outward at an angle to 40 lever 13, but not inward beyond alinement with the lever. Lever 13, besides being free to swing on arbor 12, has also a slight axial movement thereon, so as to be able to override abutment 16. By imparting a substantial Z shape to lever 13, its inner wing will 45 find a bearing on base plate 10, to which it is fulcrumed, while a clearance is obtained between the door and the outer wing that permits the tilting of finger 18.

From the upper edge of the central stem of lever 13, there extends an integral prong or hammer 20 adapted to strike a locking pin 21 influenced by a spring, 21^a, and arranged within the casing 22 of a suitable alarm bell 23. This locking pin, when advanced, 50 crowds against the bent stem 24 of the clapper 25, and thus holds the same off gong 23. When the locking pin is retracted, the clapper is released and will be actuated by the alarm spring, (not shown), through a train 55 of gearing 26 and an escapement wheel 27 coöperating with the anchor 28 of the clapper in the usual manner.

Upon the central spindle 29 of the alarm bell there is rotatably mounted a shield 30 60 having a handle 31 which protrudes outwardly between casing 22 and bell 23. When the alarm is to be rendered inoperative, shield 30 is, by its handle 31, so turned on spindle 29, as to become interposed between clapper 25 and bell 23, (Fig. 4).

In use, the tenant, on departing, opens the door, sets lever 13 across the door-opening, and on leaving closes the door behind him, (Fig. 1). This closing of the door can be 75 accomplished without setting off the alarm, because finger 18 can swing outward freely on lever 13. If a person attempts to enter, the door, on swinging inward, will cause finger 18, by stop-hinge 19, to tilt lever 13 on 80 arbor 12, and thereby cause the lever to override abutment 16. The lever being thus released, will, by spring 15, be projected upward, so that its hammer 20 strikes locking pin 21 and thus moves the same out of engagement with the clapper, to set off the alarm. If the tenant desires to remain at home, he 85 also swings the lever 13 across the door, so that the latter will set off the alarm on being opened.

It will be seen that the alarm is of simple construction, that it is readily manipulated, and that it is reliable in operation.

I claim:

1. A burglar alarm, comprising a base 95 plate, a spring influenced lever of substantial Z-shape to form an inner and an outer wing, means for pivoting the inner wing to

the base plate, a finger, a stop hinge connecting the finger to the outerwing, and means on the lever for releasing an alarm sounding means, substantially as specified.

5 2. A burglar alarm, comprising a spring-influenced lever having a hammer, a locking pin adapted to be engaged by the hammer, a clapper controlled by the pin, a bell, and a rotatable shield adapted to be interposed be-

tween bell and clapper, substantially as 10 specified.

Signed by me at New York city, (Manhattan,) N. Y., this 16th day of May, 1908.

HERMAN WETTSTEIN.
